UNITED STATES PATENT OFFICE

FRED C. STAVER, OF AVIS, PENNSYLVANIA,

COMBINATION-LOCK.

1,338,796.

Specification of Letters Patent. Patented May 4, 1920.

Application filed September 24, 1919. Serial No. 326,067.

To all whom it may concern:

- Be it known that I, FRED C. STAVER, a citizen of the United States, residing at Avis, in the county of Clinton and State of Pennsylvania, have invented certain new and useful Improvements in Combination Locks, of which the following is a specification, reference being had to the accompanying drawings.
- 10 This invention relates to combination locks, and has for its object to provide a device of this character having a sliding bolt operated by a sliding plunger, the sliding plunger being operable only when the sliding bolt is released by the locking combination.
- 15 Another object of the invention is to provide a sliding locking bolt including an extension having a cam surface, and a sliding plunger including a cam surfaced head for moving the bolt from its locked position, and spring means for forcing the extension to return the plunger to its former position.
- 20 These objects are attained by the mechanism illustrated in the accompanying drawings, in which:—
- Figure 1 is a longitudinal sectional view;
- Fig. 2 is a top plan with the upper plate, slide plunger and operating knob removed;
- 30 Fig. 3 is a plan view of the combination working ring, operating knob and sliding plunger for opening the lock;
- Fig. 4 is a detail view of the locking bolt and spring;
- 35 Fig. 5 is a plan view of the lower combination disk;
- Fig. 6 is a plan view of the intermediate combination disk;
- 40 Fig. 7 is a plan view of the upper combination disk;
- Fig. 8 is a plan view of the head and sliding plunger, showing its connection to the guide plate;
- 45 Fig. 9 is a detail perspective view showing the relative positions of the locking bolt and sliding plunger and their abutting cam surfaces;
- Fig. 10 is a detail view of the spindle of the combination mechanism;
- 50 Fig. 11 is a detail view of the washer disposed between the combination disks;
- 55 Referring to the drawings, 5 indicates an upper plate and 6 a lower plate. Secured to the upper plate is a spindle 7, having a groove 8. This spindle is intended to support the combination mechanism. Rotata-
- bly mounted in a center opening 9 in the spindle 7 is a shaft 10 having an operating knob 11 including a flange 12 provided with an indicating mark 13, which registers with 60 indications on an adjacent ring 14 carried by the door on which the lock is used. The remaining end of the shaft 10 is provided with a plate 15. Rotatably mounted on the spindle 7 is a plurality of combination disks 65 16, 17 and 18. The disk 16 has a peripheral recess 19 and a plurality of openings 20 in one of which a pin 21 is secured. The disk 17 has a semi-circular slot 21', a plurality of openings 22 and a peripheral recess 23. 70 Disposed in one of the openings 22 is a pin 24. The disk 18 has a semi-circular slot 25 and a peripheral recess 26. The pin 21 of the disk 16 is intended to be disposed in the slot 21' of the disk 17, while the pin 24 of the disk 17 is intended to be disposed in the slot 25. A washer 27 having an inwardly extending lug 28 is disposed between each of the disks, and has its lug 28 engaged in the slot 8 of the spindle 7 to prevent rotation of the washer. The plate 15 of the shaft 10 is secured to the disk 16 and is intended to rotate said disk. The remaining disks are rotated by the pins 21 and 24. The openings 20 and 22 in the disks 16 and 17 are intended to receive the pins 21 and 24 when it is desired to change the combination. 80
- A sleeve 29 is carried by the plate 5 and is intended to support a sliding plunger 30 90 having at one end an operating knob 31 and at its other end a head 32. One end of the head 32 is dove-tailed as at 33. The head is also beveled as at 34 to provide a cam surface. Carried by the plate 5 is a guide plate 35 having a dove-tailed groove 36 adapted to receive the dove-tailed ends of the head 32, to position and guide the same. This plunger is slideable in the sleeve 29 to operate the locking bolt of the lock when the 95 bolt is released by the combination mechanism.
- Carried by the plate 6 is a pair of longitudinally L-shaped guide bars 37, adapted to receive the sliding bolt 38. A pin 37' depends from each guide member and is adapted to engage openings 36' in the guide plate 35 to hold the same in position. 100
- The bolt 38 comprises a plate 39 having projecting from one end a locking head 40. 110 The sides of the plate 39 extend beyond the sides of the head 40 and are intended to be

received by the guide members 37, to slidably support the bolt. Projecting upwardly from the other end of the plate 39 in spaced relation to the sides thereof is an extension 5 or locking wing 41, the base 42 of the extension being of greater width than the end 43, and is inclined or beveled toward the top 44 of the extension to provide a relatively wide cammed surface 46 adapted to 10 engage the cam surfaced head 32 of the sliding plunger. A coil spring 47 is secured at its end 48 to the plate 6, the remaining end 49 being secured to the base of the extension 41 and is intended to move the locking bolt 38 to its locked position when the latter is released by the sliding plunger.

When the lock is assembled, the end of the shaft 10 extends through the plate 6, while the pins 37' of the guide members 37 are 20 positioned in openings 36' in the guide plate 35. The guide plate 35 extends transversely of the bolt 38 between the extension 41 and the locking head 40, so as to position the cam surfaced head 32 beneath and in abutting 25 relation with the cam surface 46 of the extension 41, to permit the head 32 to limit the locking bolt in its locking movement, and also to engage the rear portion of the locking head 40 to limit the unlocking movement of the bolt 38.

In operation, the operating knob 11 is rotated in one direction to cause the pins 21 and 24 to engage the disks 17 and 18 and permit the shaft 10 to rotate all of the disks until the 35 indicating mark 13 registers with a certain combination mark on the ring 14 and thereby position the recess 26 of the disk 18 in alinement with the extension 41. The knob is then rotated in the opposite direction so 40 as to permit the pin 21 to engage the disk 17 and bring the recess 23 thereof in alinement with the extension 41 and in registration with the recess 26 of the disk 18. During this movement, the pin 24 moves idly in 45 the slot 25 so as not to disturb the disk 18. The knob 11 is once more moved in the direction first mentioned, which causes the rotation of the disk 16 independently of the disks 17 and 18, the disks 16 being rotated 50 until the indicating mark 13 registers with a combination mark on the ring 14. This causes the recess 19 of the disk 16 to register with the recesses 23 and 26 in alinement with the extension 41. The sliding plunger 55 30 is then moved through the sleeve so as to engage the head 32 with the cam surface 46 of the extension 41, and move the bolt by means of the extension into the registering peripheral recesses against the tension 60 of the spring 47, and thereby release the locking bolt. When the sliding plunger 30 is released, the force of the coil spring 47 forces the extension into engagement with the cam surfaced head 34, and moves the 65 same through the sleeve to its former posi-

tion and at the same time causes the head 40 of the bolt 38 to move to its locking position.

From the foregoing, it will be readily seen that this combination lock provides a novel 70 sliding bolt, operated by a plunger which does not require any unusual effort on the part of the operator such as turning to the right or left, but is simply pushed inwardly after the combination has been worked, to 75 release the sliding bolt. In addition to this it provides additional security for the lock should the combination be operated by an unauthorized person, as it has the appearance of a knob to be turned. 80

What is claimed is:

1. A lock comprising a series of combination disks, each having a recess, two of said disks having a series of openings, a pin carried by each of the last mentioned disks, 85 two of said disks having semi-circular slots adapted to receive the pin of the adjacent disk, means for rotating said first mentioned disk, a bolt, and a manually operated means arranged to move the bolt into the registering 90 recesses of the disks.

2. In a combination lock, the combination with a series of combination disks, each having a recess and operatively connected to each other, of a sliding bolt, a sliding 95 plunger operatively engaged with the bolt to move the same into the registering recesses of the disks and a spring connected to said bolt for projecting the same from the recesses in the disks when the plunger 100 is released.

3. In a combination lock, the combination with a series of combination disks, each having a recess and operatively connected to each other, of a sliding bolt, an extension 105 carried by said bolt and arranged to enter the recesses of the disks, a sliding plunger intersecting said bolt and operatively engaged with the extension to move the same into the recesses of the disks and a spring 110 connected to the extension for ejecting the same from said recesses and disengaging the plunger from the extension when the latter is released.

4. In a combination lock, the combination 115 with a series of combination disks, each having a peripheral recess and operatively connected to each other, of a sliding bolt, an extension carried by said bolt and arranged to enter the recesses of the disks, a sliding plunger intersecting said bolt and operatively engaged with the extension to move the same into the peripheral recesses of the disks and a spring connected to the extension 120 for projecting the same from said recesses and disengaging the plunger from the extension when the latter is released, the plunger limiting the locking movement of the bolt. 125

5. In a combination lock, the combination 130

- with a series of combination disks, each having a peripheral recess and operatively connected to each other, of a sliding bolt having a projecting locking head at one end, 5 and an extension at its other end, and a sliding plunger intersecting said bolt between the locking head and the extension, and arranged to operatively engage the extension to move the same into the peripheral recesses of the disks.
6. In a combination lock, the combination with a series of combination disks, each having a peripheral recess and operatively connected to each other, of a sliding bolt having 15 a projecting locking head at one end, and an extension at its other end, and a sliding plunger intersecting said bolt between the locking head and the extension, and arranged to operatively engage the extension 20 to move the same into the peripheral recesses of the disks, said extension and sliding plunger having abutting cam surfaces.
7. A lock comprising a locking member shiftable to projected and retracted positions, manually operable means intersecting the bolt for shifting the bolt to a retracted position, means for projecting the bolt upon release of the manually operable means, and a plurality of tumblers normally preventing 25 the retraction of the bolt and manually shiftable into position to permit the retraction of the bolt.
8. A lock comprising a locking member shiftable to projected and retracted positions, manually operable means intersecting the bolt for shifting the bolt to a retracted 30 position, means for projecting the bolt upon release of the manually operable means, and a plurality of tumblers normally preventing the retraction of the bolt and manually shiftable into position to permit the retraction of the bolt.
9. A lock comprising a locking member shiftable to projected and retracted positions, means intersecting said bolt and laterally movable with respect to the bolt for shifting said bolt to a retracted position, means for projecting the bolt upon release 35 of the first mentioned means, a plurality of tumblers normally preventing retraction of the bolt and manually shiftable into position to permit retraction of the bolt, and a member intersecting the bolt, said member 40 guiding the first mentioned means and limiting the retracting movement of the bolt.
10. A lock comprising a locking member shiftable to projected and retracted positions, means intersecting and engaging the bolt at all times, said means being movable for shifting the bolt to a retracted position, means for projecting and causing the bolt to move the first mentioned means upon release of said first named means, and a plurality of 45 tumblers normally preventing retraction of the bolt and manually shiftable into position to permit retraction of the bolt.

In testimony whereof I hereunto affix my signature.

FRED C. STAVER.
